AUTOMATIC CAR COUPLER

George T. Johnson and George M. Murphy, Co-
lumbus, Ohio, assignors to The Buckeye Steel
Castings Company, Columbus, Ohio

Application May 17, 1929, Serial No. 363,759

7 Claims. (Cl. 213—122)

This invention relates to improvements in automatic car couplers. Such couplers usually include a coupler head, a knuckle pivotally mounted on the head and provided with a tail, a vertically slideable lock adapted to engage the tail for holding the knuckle in closed position, and means for raising the lock. The present invention is directed specifically to improvements in the lock raising means, and the primary object of the invention is to provide a coupler of this character, including a lock lifter which may be removably connected to the lock when the latter is in a certain position, and before the knuckle has been pivotally connected to the coupler head, the connection of the lifter with the lock being such, and the parts being so arranged that after the knuckle is pivotally mounted on the coupler head, the lifter cannot be detached from the lock without first removing the knuckle from the coupler head.

A further object is to provide a construction of this type, in which the cross section of the lifter varies in such a way that when the lock is in its highest position, the lifter may be turned through a slot in the top of the coupler head, for the purpose of connecting the lifter to the lock, but when the lock is slightly lowered, the cross section of the lifter at the place where the slot occurs, will be too thick to allow the lifter to be rotated in a reverse direction, with a view of detaching the lifter from the lock.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings,

Fig. 1 is a front elevation of the upper part of the coupler head with the lifter extending into the lock but shown in the position which it occupies before the lifter is turned 90 degrees for interlocking the lower end of the lifter with the lock.

Fig. 2 is a front elevation of the coupler head before the knuckle has been attached thereto, and showing the lifter after the latter has been turned 90 degrees from the position shown in Fig. 1, in order to interlock the lifter with the upper end of the lock.

Fig. 3 is a side view of the complete assembly, with certain parts broken away to facilitate disclosure of the invention, and with the lock and lifter shown in the highest positions they can

reach, after the knuckle has been connected to the coupler head.

Fig. 4 is a top plan view of the structure shown in Fig. 3, and illustrating the manner in which the tail of the knuckle functions to prevent the lock from rising beyond a predetermined elevation after the parts have been assembled.

Fig. 5 is a front elevation of the complete assembly, but showing the lock in its lowermost or locking position.

Fig. 6 is a horizontal sectional view on the line 6—6 of Fig. 5, with the lifter removed.

Fig. 7 is a side elevation of the lifter.

Fig. 8 is a similar view of the lifter, but taken at a point removed 90 degrees from that on which Fig. 7 is taken.

Fig. 9 is a horizontal sectional view of the lifter on the line 9—9 of Fig. 7.

Fig. 10 is a top plan view of the lifter.

Fig. 11 is a bottom plan view of the same.

Fig. 12 is a diagrammatic view, supposedly taken on the line C—C of Fig. 8, to illustrate how the portion of the smaller cross section of the lifter may be rotated in the slot.

Fig. 13 is a similar view, supposedly taken on the line D—D of Fig. 8, and showing how a thicker portion at a higher point on the lifter is prevented from rotating in the slot.

Fig. 14 is a front elevation, partly in vertical section, of the lock.

Fig. 15 is a side elevation of the same, partly in vertical section, the section being taken on line 15—15 of Fig. 14.

Fig. 16 is a top plan view of the lock.

In the drawings, 20 designates a coupler head which has its front wall slotted as shown at 21, to permit a vertically slideable lock 22 to be inserted into a vertical guideway 23, within the coupler head. The head is also provided with apertured ears 24 which receive the pin 25 employed in pivotally connecting the knuckle 26 to the head.

When the parts are assembled, a tail 27 of the knuckle is inserted through the opening 21, into the head, and this tail in the opening and closing movements of the knuckle, travels in a hollow lateral extension 28 of the head. From Fig. 6, it may be seen that the knuckle has an abutment surface 29 adapted to engage a similar surface 30 on the coupler head, to limit the opening movement of the knuckle.

The tail 27 works in a notch 31 of the lock, and as the under side of the edge portion of the tail is inclined from its front end 32 to its extremity 33, it may be seen from Fig. 3 that when

110

the lock 22 is raised, an inclined nose 34 on the lower end of the lock will cooperate with the tail for the purpose of swinging the knuckle into open position.

5 The parts 20 to 34 inclusive are of more or less conventional construction, and the present improvements are concerned particularly with the lifting of the lock. To this purpose, the head of the lock, as best shown in Figs. 14 and 15, 10 is provided with a cavity indicated generally by the reference character 35. The walls of this cavity are shaped in a particular manner, to provide an entrance slot 36 and a pair of segmental recesses 37. These recesses are oppositely disposed, and the top portion of each recess terminates in a semi-cylindrical or arc-shaped abutment 38. This special formation is provided to allow the lower end of the lock lifter 15 39 to be inserted through the slot 36, into the cavity 35, and then be turned 90 degrees in order to bring trunnions 40 at the lower end of the lifter, into engagement with the semi-cylindrical abutments 38 of the recesses 37. In order that this feature of the invention may be more 20 clearly understood, reference is made to Figs. 7 to 13 inclusive. From Figs. 7 and 8, it will be noted that the body of the lifter 39 is substantially an I-section with a loop or eye 41 on the upper end, for the purpose of joining the lifter 25 to the operating rod (not shown). The portion 42 of the lifter, as shown in Fig. 8, between section A—A and B—B gradually changes from an I-section to a circular section. The importance of the outline of this portion 42 will be explained 30 later. The lower end portion 43 of the lifter is of circular section, and provided with the diametrically oppositely extending trunnions 40, heretofore referred to.

At this point it will be noted that the slot 44 35 in the top of the coupler head, through which the lifter is inserted, is of rectangular formation, and only slightly larger than the limits of the body of the lifter 39. The head of the lock 22 is, of course, too large to pass through the slot 44.

The main body of the lock 22 is practically the same as the locks heretofore known, the only difference being in the cavity 35 with its entrance slot 36, segmental recesses 37 and abutments 38, 40 which receive the lower end of the lifter 39. The slot 36, as best shown in Fig. 16, is rectangular in plan, and the lower portion of the cavity 35 formed by the recesses 37 is cylindrical, except for the lugs 45 which permit the lifter to 45 be applied only one certain way. As before stated, the abutments 38 are provided to take the trunnions 40 of the lifter.

To assemble the coupler, the lock 22 is introduced through the opening 21 into the vertical guideway 23, and raised to its highest position, 50 as shown in Fig. 1. The lower end of the lifter 39 is then inserted through the slot 44 in the top of the coupler head, until it rests on the floor 46 of the opening in the head of the lock. Then the lifter is turned 90 degrees in a clockwise direction (see Fig. 16), and the lock allowed 55 to drop, so as to engage the trunnions 40 of the lifter with the abutment 38 of the lock. At this point it will be observed that the lugs 45 in the head of the lock, prevent the trunnions from turning in the wrong direction while the parts are being assembled.

Now the knuckle 26 is secured to the head by the pin 25, and the tail of the knuckle projects 75 over the nose 34 of the lock, so that the lock

can no longer be raised to its highest position, unless the knuckle is removed from the coupler head.

When the lock is in its highest position, the lower portion of the part 42 of the lifter occupies the slot 44, as indicated in Figs. 8 and 12, and at such time, the lifter can be readily turned in the slot 44, due to the fact that the thickness of the part 42 at this elevation, is less than the width of the slot. However, after the parts are assembled, the lock cannot be lifted any higher than the position indicated by X in Fig. 3, and at this time, the upper portion of the part 42 of the lifter will be occupying the slot 44. As indicated in Fig. 13, and by the line D—D in Fig. 8, the lifter cannot be removed at such time, because the diagonal thickness of the lifter, when the trunnions 40 are low enough to clear the abutments 38, is greater than the width of the slot 44, so that the lifter can no longer be turned in the slot 44. Therefore, there is no danger of the lifter becoming dis-engaged from the lock, and there is no danger of theft, unless the coupler is completely dismantled.

When the lock is in locked position, as shown 100 in Figs. 5 and 6, it occupies a position between the tail of the knuckle and a wall 47 of the lock guideway 23, and is located at the lower end of its guideway. Consequently, the eye 41 of the lifter rests on the top of the coupler head, 105 and retains the trunnions 40 in engagement with the abutments 38 in the lock.

From the foregoing it will be understood that when the knuckle 26 has been placed and its pivot pin 25 inserted, as shown in Fig. 3, the lock 110 22 cannot rise above the position X in Fig. 3, because of the contact between the part 48 of the knuckle and the inclined surface of the nose 34 of the lock. For example, when the knuckle 115 is in open position, as shown in Fig. 4, the lock cannot be lifted to its highest position, as in Fig. 2, because of the contact with the knuckle tail, as indicated at Z in Fig. 4.

On closing the knuckle, the lock drops to the position shown in Fig. 5, filling the space between the knuckle tail and the coupler wall 47, and preventing the knuckle from opening, as best shown in Fig. 6 until the lock is lifted.

The terms and expressions employed herein are used as terms of description and not of limitation, and there is no intention in the use of such terms and expressions, of excluding any mechanical equivalents of the features shown and described or portions thereof, but it is recognized that various structural modifications are possible within the scope of the invention claimed.

What is claimed and desired to be secured by Letters Patent is:

1. In a car coupler, a coupler head, a knuckle 135 movably mounted on the head, a lock for securing the knuckle in closed position, means in the head for guiding the lock in a substantially vertical rectilinear path, a lifter, and connecting means for interlocking the lifter with said lock, the lifter being capable of disconnection from the lock by a rotary movement of the lifter about its long axis 140 relatively to the lock after the latter has reached its uppermost position, and means including said knuckle for preventing disconnection of the lifter 145 from the lock when the latter is in other positions.

2. In a car coupler, a coupler head, a knuckle 150 movably mounted on the head, a lock for securing the knuckle in closed position, a lifter, and con-

- necting means for interlocking the lifter with said lock, the lifter being capable of disconnection from the lock by a rotary movement of the lifter about its long axis relatively to the lock, after the latter has reached a certain position, said knuckle preventing the lock from moving to such position when the parts are completely assembled.
3. In a car coupler, a coupler head, a movable knuckle mounted on the head, a lock cooperating with the knuckle for securing the latter in closed position, means forming part of the head for guiding the lock in a substantially vertical path, a lifter extending through the top of the coupler head, and means connecting the lifter to said lock, the lifter being capable of attachment to or detachment from the lock by a rotary movement of the lifter about its long axis relatively to the lock, after the latter has reached its uppermost position, the knuckle cooperating with the lock to prevent the lock from moving into said position after the parts are assembled, and the knuckle being removable from the head to permit the lock to reach said position.
- 25 4. In a car coupler, a coupler head, a movable knuckle mounted on the head, a lock cooperating with the knuckle for securing the latter in closed position, said lock being guided against rotation relative to the coupler head in all vertical positions, a lifter extending through the top of the coupler head, and means connecting the lifter to said lock, the lifter being capable of attachment to or detachment from the lock by a rotary movement of the lifter about its long axis relatively to the lock, after the latter has reached its uppermost position, the coupler head and lifter being provided with abutment surfaces for preventing such relative movement between the lifter and the lock, when the lock is in any other position, the knuckle being removable from the head, said lock being capable of reaching said uppermost position after the knuckle has been removed.
5. In a car coupler, a coupler head, a knuckle pivotally mounted on the head and provided with a tail, a lock movably mounted in the head and cooperating with the tail for securing the knuckle in closed position, a lifter for the lock, and means detachably connecting the lifter to the lock, the lifter being capable of disconnection from the lock when the lifter is turned about its long axis, while the lock is in one of its extreme positions, the tail of the knuckle preventing the lock from reaching such position after the parts are assembled, the knuckle being removable to permit the lock to reach said extreme position.
- 80 6. In a car coupler, a coupler head provided with a slot, a vertically slidable lock arranged in the head, said lock being guided against rotation relative to the coupler head in all vertical positions, a lifter extending through said slot, and means detachably connecting the lifter to the top of the lock, the lifter being capable of detachment from the lock by a rotary movement of the lifter about its long axis relatively to the lock, the lifter and slot cooperating to prevent such relative movement until the lock has been placed in its uppermost position.
- 90 7. A car coupler including a coupler head having a slot therein, a lifter extending through said slot and having trunnions at its inner end and connection means at its outer end, the part of the lifter between the trunnions and said connection means having portions of varying cross section, the portion adjacent to the trunnions being less in width and thickness than the width of said slot and the remaining portion being greater in width and thickness than the width of said slot to prevent the lifter from being turned in the slot except when the lifter is in its outermost position.
